CLAIM

The ornamental design for jewelry, as shown and described.

DESCRIPTION

FIG. 1 is an isometric view of an ornamental design for jewelry;

FIG. 2 is a front elevational view thereof;

FIG. 3 is a rear elevational view thereof;

FIG. 4 is a right side elevational view thereof;

FIG. 5 is a left side elevational view thereof; and,

FIG. 6 is a top plan view thereof.

The broken lines at the top and at the sides of the design are for the purpose of illustrating ornamentation and forms no part of the claim.

1 Claim, 6 Drawing Sheets
